UNITED STATES PATENT OFFICE.

JAMES HERVA JONES, OF ROCKFORD, ILLINOIS.

CORN-PLANTING MACHINE.

SPECIFICATION forming part of Letters Patent No. 254,381, dated February 28, 1882.

Application filed June 20, 1881. (Model.)

To all whom it may concern:

Be it known that I, JAMES HERVA JONES, a citizen of the United States, residing in the city of Rockford, in the county of Winnebago 5 and State of Illinois, have invented a new and useful Improvement in Corn-Planting Machines, of which the following is a specification.

My invention relates to that class of planters known as "power-planters," in which a team is employed to draw the machine over the ground prepared to receive the seed.

The invention consists in the improved construction hereinafter described, and pointed out in the claims.

15 In the accompanying drawings, Figure 1 is an isometrical representation of a planting-machine embodying my invention. Fig. 2 is an isometrical representation of the runner-frame or forward portion of the planter. Fig. 20 3 is a side elevation. Fig. 4 is a lengthwise vertical section through the heel of the runner and drill seed-tube. Fig. 5 is also a lengthwise vertical section of heel of the runner, seed-spout, and flipper-valves of the check-row 25 mechanism. Fig. 6 is an isometrical representation of the working-face of the fixed disk of the seeding mechanism. Fig. 7 is an isometrical representation of the working-face of the rotary seeding-disk. Fig. 8 is a vertical section on dotted line α of Fig. 1. Fig. 9 is an isometrical representation of the lower flipper-valve, and Fig. 10 is an isometrical representation of the upper flipper-valve.

The several parts represented in the drawings—consisting of the runners A, the inclined seed-spouts B, connected with the open heel of the runners, the rear transverse beam, C, connecting the upper portion of the seed-spouts, the oblique horizontal beams D, connected 35 40 with the under side of the end portions of the transverse beam C and with the forward upturned end of the runners, and the forward transverse beam, E, connected with the forward end portion of the oblique beams D immediately over the forward end of the runner—45 are substantially the same, and are joined in the same manner, producing a frame substantially the same as the frame shown and described in my application for a patent on corn-50 planting machines now pending before the United States Patent Office, and which said

application was filed therein on or about March 17, 1881. On this frame, immediately over the upper open end of the seed-spouts, are mounted seed-boxes F, consisting mainly of the vertical outer wall, a , end walls, a' , and inner side wall, a'' , suitably joined, producing a receptacle to contain the seed to be distributed through the spouts. 55

At G are represented metallic disks provided with a tapering spout-like grooved opening, b , crossing their rear face and extending beyond their periphery, which extensions are formed in an arm, b' , depending from their periphery. The upper wide end portions of these 60 spout-like grooves on their upper edge portion open on their inner face, as at c , a considerable distance within their periphery, and the bases of these openings are concentric with the peripheries of the disks, and are beveled from 65 their inner edge rearward, as at d , in such a manner as to form an edge on their periphery. 70

These disks are fixed to the inner face of the outer ends, e , of the seed-boxes, having their spout-like grooved face in contact with the 75 box end, in such position thereon that the lower portion of their spout-like openings will connect with the upper end of the inclined seed-spouts leading to the open heel end of the runners. These disks are provided with a central 80 opening, f , to receive a transverse shaft, H, fitted to revolve therein, and concentric with this central opening are fitted on their inner face with a groove, h , semicircular in cross-section, and the diameter of its inner circle is 85 such as to rise slightly above the periphery of the base portion of the opening c .

At I are represented seed-distributing wheels of disk form, loosely mounted on the transverse shaft H, one in each seed-box, in 90 position to engage the inner face of the fixed disks G. These wheels are provided with a central hub, i , which is slotted lengthwise to receive a pin, i' , passed through the shaft, operating to cause the wheel to rotate with the shaft and still permit the wheel to have a slight 95 endwise movement thereon.

At j is represented a spiral spring, surrounding the shaft within the seed-box, operating to hold the rotary seed-wheels in contact with the fixed disk. This rotary seed-wheel is provided at suitable intervals with radial arms K,

projecting from its periphery to overlap the semi-circular groove in the face of the fixed disk and rise above the opening *c* in its upper portion. These radial arms are fitted near the center of 5 their length with a semicircular protection, *k'*, designed to enter the semicircular groove in the fixed disk, and the end portions of these radial arms on each side of the projections *k'* are of semi-cup form, as at *k''* and *k'''*, being 10 largest at their outer ends and diminishing as they approach the central outward projection, *k'*. These semi-cups, in connection with the semicircular groove in the face of the fixed disk, form the cups employed to distribute the 15 seed.

The seed-cups *k'''* on one side of the projecting arms *k'* are slightly larger than the cups *k''* on the opposite side thereof, and these seed-distributing wheels are made in pairs in 20 such a manner that when placed in their respective seed-boxes the seed-cups on the forward moving side of the wheels carrying the seed will be of the same size, either both large, as at *k'''*, or both small, as *k''*, and by changing 25 these seed-wheels to their respective opposite sides, either the large cups *k'''* or the small cups *k''*, as the case may be, will be on the forward moving side of the wheels, and will be employed in the distribution of the seed, and 30 the different-sized cups are designed to distribute seed varying in size. These seed-cups, as will be seen, rise above the periphery of the cut-away portion of the fixed disk in such a manner as to discharge the seed into the seed-spouts as it is carried up in the seed-cups in 35 the revolutions of the seed-distributing wheels. These seed-distributing wheels, as will be seen, are mounted to revolve in the seed-boxes in contact with the seed therein contained.

40 At *l* is represented a tubular seed-spout removably placed in the open seed-spout connected with the heel of the runner in such a manner that its upper open end connects with the seed-spout *d* in the fixed disk, and its 45 lower end portion, which is of bent-elbow form, enters the open heel portion of the runner in a vertical position. This tubular spout is held in position in the open spout by means of a spring-fastening, *l'*, which enters a hole formed 50 in the under portion of the open spout and operates to hold the tubular spout in position in a removable manner. This tubular spout is employed only when the machine is used as a drill, and for such purposes the tube is employed 55 in both open spouts or on both sides.

At *m* is represented a flipper-valve, substantially the same as the flipper-valve in my pending application, hereinbefore referred to, and it is pivoted in the open seed-spout in the same 60 manner by means of a pivot, *m'*, depending from its lower edge, entering a hole in the under side of the open spout, and the upper end of its lever-arm *m''* engages the notch *m'''* in the rear edge of the slide-bar *K*, employed to 65 connect the flipper-valves on the opposite sides of the machine. The upper end of the blade

of the flipper-valve *m* engages the lower forked end of a check-valve, *n*, which is pivoted in the upper portion of the open seed-spout by means of a pivot-stud, *n'*, depending from its lower 70 edge, and entering a hole in the under side of the open spout, substantially in the same manner as the flipper-valve *m*. From this connection of the valves with each other and with the slide-bar it will be seen that in the 75 movement of the slide-bar the valves will be changed from one side of the spout to the opposite side thereof, in which movement the seed deposited on the check-valve will be dropped therefrom, and will be caught on the 80 flipper-valve in the heel of the runner, near the bottom of the furrow formed by the runner, and in the next movement of the slide-bar it will be dropped therefrom in a compact hill. These valves are designed to be used in 85 both runners, to be operated simultaneously by the movement of the slide-bar, when the machine is used as a check-row or hill planting-machine, and, as will be seen, are made removable by withdrawing the pins or colters 90 *n''*, which are passed through the depending end portions of their pivotal studs, extending below the under portion of the open seed-spouts.

From the foregoing it will be seen that both 95 the seed-tubes and the valves are made removable, and the machine is capable of use as a drill or as a check-row or hill planter by the employment of the seed-tubes for the purposes of a drill, or by the employment of the valves 100 for the purposes of a check-row or hill planter.

The slide-bar *K* is capable of an endwise movement, to be operated by means of a hand-lever, *L*, having its fulcrum-support *n'''* fixed to the inner upper portion of the seed-boxes, 105 and the lever *L*, pivoted thereon, is substantially identical with the like lever represented in my pending application, hereinbefore referred to, and its pivotal connection and its connection with the slide-bar are in every particular the same, and I do not deem it necessary to give a more detailed description thereof in this specification. This front or runner portion of the planter is provided with a tongue or pole, *M*, of the usual form, having its rear 110 end fixed centrally to the rear transverse bar, and supported centrally on the front transverse bar, to which it is securely fixed.

At *N* is represented a rear extension of the pole fixed to the under side of the rear end 115 portion of the pole *M* and to the under side of the rear transverse bar, from which it extends rearward, for a purpose to be hereinafter described.

At *O* is represented an axle-tree of suitable 120 dimensions, and to its end portions are fixed axle-arms *p*, fitted to receive the carrying-wheels *P*, to revolve thereon in the usual manner.

At *R* are represented hounds or inclined 125 beams, having their rear portions fixed to the under side of the end portions of the axle-tree,

from which the forward end portions incline toward each other, having their forward end portions fixed to the outer portions of a metallic cross-head or yoke, S. The end portions of the front edge of this yoke are produced in journal form, as at p', which enter the socket-bearings p'', fixed to the rear face of the rear transverse bar of the runner-frame. These socket-bearings p'' are of oblong form, being of a proper width horizontally to receive the journal-bearings of the yoke snugly, to prevent lateral swaying of the front or runner frame independent of the rear or wheel frame. The vertical dimensions of these socket-bearings are of slot-like form, of sufficient length to permit of a vertical rocking movement of the runners sufficient to permit the machine to adapt itself to the inequalities of the ground. This journal-connection of the yoke with the socket-bearings fixed to the runner-frame serves to produce a hinge-joint connection of the front and rear frames, to permit of the independent vertical movements thereof required in a successful planting-machine.

At T is represented a seat-support, consisting of a beam of suitable dimensions, having its forward end fixed to the center of the yoke, from which point it extends rearward, inclining upward over the axle-tree, being supported thereon by means of a bracket, p''', and on its upper rear end is mounted a driver's seat, T', which is of the usual form.

At r is represented a two-branch lever, formed to embrace the seat-support, to which it is centrally pivoted, having its upper end within easy reach of the driver when mounted in his seat. The upper portion of this lever is connected to the rear extension of the pole by means of a link, r'', of rod form, passing through a slot in the inclined beam prepared to receive it, and bent in such a manner as to be self-sustaining when in the position as represented in Fig. 1 and in dotted lines at Fig. 3, operating to hold the runner-frame elevated, as represented in dotted lines, and when in the position of solid lines, as in Fig. 3, will permit the runner-frame to descend to its working position and limit its descent, as represented in the solid lines. The two branches of this lever at their lower ends are provided with a lateral arm, r''', extending from their lower ends outward, and are designed to receive the feet of the driver, to enable him to raise the runner-frame and change the position of the lever to bring the cross-bar r'''' at its upper end within easy reach.

At s is represented a beveled-toothed gear-wheel mounted on the end of the transverse shaft H on the outside of the seed-box.

At s' is represented a tubular shaft having its forward end portion fitted with a spherical enlargement, s'', forming a bearing to enter the socket-bearing, s''', formed in the upper end of its bracket-standard in such a manner as to produce a flexible ball-and-socket bearing.

At s⁴ is represented a beveled-toothed gear-

wheel mounted on the tubular shaft in such relative position with the gear-wheel on the outer end of the transverse shaft that their gear-teeth will engage each other in working contact. The free end of this tubular shaft is produced in saw-toothed clutch form.

At t is represented a shaft having its forward end supported to revolve in the tubular shaft, and capable of an endwise sliding movement therein. The rear end portion of this shaft is fitted to revolve in a tubular bearing, t', supported on the outward-projecting end of the axle-arm of the carrying-frame. This shaft, immediately forward of its rear end bearing, t', is provided with a beveled-toothed gear-wheel, t'', having its teeth engage the teeth of a beveled-toothed gear-wheel, t''', mounted on the outward-projecting hub of the carrying-wheel. The rear end of the shaft t, projecting rearward of its bearing, is fitted with a collar, t⁴, which, in connection with the beveled-toothed gear-wheel t'', operates to prevent endwise movement in its tubular bearing t.

At u is represented a tubular saw-toothed clutch mounted upon the shaft t in such relative position with the saw-toothed clutch of the tubular shaft that their clutch-teeth shall engage each other when the machine is in working position. This rear portion, u, of the clutch is slotted lengthwise on opposite sides, as at u', to receive a pin, u'', passed through the shaft, and operates to cause the clutch to revolve with the shaft, and to permit of a limited endwise movement of the clutch thereon.

At u''' is represented a spiral spring surrounding the shaft t', immediately in rear of the clutch, operating to hold the clutch in its forward position on the shaft by its spring action, but in such a manner as to permit a rearward sliding action of the clutch against the action of the spring to prevent injury to the parts.

From the foregoing it will be seen that when the machine is in working position the clutch-teeth will engage each other, and in the forward movement of the machine a rotary motion will be imparted to the seed-wheels, causing them to revolve in the grain contained in the seed-boxes; and in their revolutions the cups will receive the seed, and are designed to contain but a single grain of corn, which, in the revolutions of the wheels, will be carried up and discharged from the cup through the opening c in the upper portion of the fixed disk, and will descend through the spout b and through the tubular spout l when used as a drill, and when used as a check-row or hill planter the seed, a grain at a time, will be deposited on the check-valve, from which it will be dropped onto the flipper-valve by the movement of the slide-bar, and in the next movement of the slide-bar will be dropped from the flipper-valve through the open heel of the runner and deposited in hill form in the bottom of the furrow formed by the runner, and the outward movement of the machine will cause the carrying-wheels to

pass over the hill and close the furrow thereon, which completes the operation of planting.

When the forward or runner frame is raised, as represented in the dotted lines, the clutching mechanism will be disengaged, and the distribution of the seed will be stopped. This disconnecting action of the clutching mechanism in the raising of the runner-frame is produced by reason of the triangular position of the hinge-joint connecting the front and rear frames, and the connection with the two frames of the gear-shaft on which the clutching mechanism is mounted, which will be clearly understood by an inspection of Fig. 3 of the drawings.

In this application I have neither described nor shown a seat on which to carry an attendant to operate the valves when the machine is used as a check row machine; but for this purpose any known form of seat capable of use on this machine may be employed for the purpose.

I claim as my invention—

1. The herein-described seed-distributing wheels, having radial arms provided with opposite semi-seed-cups and capable of use on either side of the machine, substantially as and for the purpose hereinbefore set forth.

2. The herein-described seed-distributing wheels, having radial arms provided with opposite semi-seed cups, varying in size, the respective sizes of said cups being on the same

side of the radial arms, and said wheels made in pairs and capable of use on opposite sides of the machine, for the purpose of distributing seed varying in size, substantially as hereinbefore set forth. 35

3. The combination, with the fixed disk having the semicircular groove, of the herein-described seed-distributing wheels, mounted loosely on the transverse shaft to revolve therewith, and a spring operating to hold the seed-distributing wheels in contact with the fixed disk, substantially as set forth. 40

4. The herein-described seed-distributing wheels, having semicircular projections extending from their face side, forming the bottom of the seed-cups, in combination with a fixed disk provided with a semicircular groove adapted to receive the semicircular projections, substantially as and for the purpose hereinbefore set forth. 45

5. The combination of the herein-described rotary seed-distributing wheels, having semi-cups, as described, with a fixed disk having a semicircular groove on its face, and its upper peripheral portion cut away opposite the seed-conducting spout within the semicircular groove, substantially as set forth. 55

JAMES HERVA JONES.
